(57) **CLAIM**

The ornamental design for a tire, as shown and described.

DESCRIPTION

FIG. 1 is a left elevation view of first embodiment of a tire, the opposite being identical thereto;

FIG. 2 is a front left perspective view thereof showing our new design, the opposite side perspective being identical thereto;

FIG. 3 is a front elevation view thereof;

FIG. 4 is a sectional view taken along line 4-4 of the tire shown in FIG. 3;

FIG. 5 is a left elevation view of a second embodiment of a tire, the opposite being identical thereto;

FIG. 6 is a front left perspective view thereof showing our new design, the opposite side perspective being identical thereto;

FIG. 7 is a front elevation view thereof; and,

FIG. 8 is a sectional view taken along line 8-8 of the tire shown in FIG. 7.

The dash/dash broken lines illustrate portions of the tire that form no part of the claimed design. The dot/dash broken lines seen in FIGS. 1 & 2 illustrate boundaries of the tire and form no part of the claimed design.
